Williams Oil-O-Matic Heating Corporation,
Bloomington, Ill., a corporation of Illinois

Application October 24, 1934, Serial No. 749,836

1 Claim. (Cl. 137—153)

This invention relates to improvements in draft regulators for furnaces or boilers and more particularly to a device of this character which is automatic in its operation.

5 It has long been customary to provide some means for regulating the pull or vacuum created by the up-draft in a smoke stack or chimney upon the fire in the furnace or boiler connected thereto. One means heretofore employed has 10 consisted in a hand-operated damper mounted within the stack, or pipe connection between the furnace and the chimney, usually in the form of a butterfly valve, which, upon manual rotation, partly closes the opening in the stack through which the gases from the furnace are 15 drawn into the chimney. Another means has been to apply a balanced or counter-weighted closure in the side of the stack or in the side of the chimney so regulated that when the up-draft or pull of the chimney is greater than the desired draft upon the fire, the pressure of the outside air will cause the damper to rotate and admit additional air into the stack or chimney. If such a damper is applied to the stack or pipe 20 between the furnace and the chimney within the furnace room, then the air is exhausted from the furnace room, requiring the provision of additional ventilation to the room, which is undesirable, especially in cold weather.

25 It is an object of this invention to provide a combination of the butterfly damper mounted within the stack leading from the furnace to the chimney with a counter-balanced pivoted damper in such a manner that when the up-draft or suction becomes greater than desired, the external pressure upon the counter-balanced damper will cause it to rotate, without admitting air to the stack, and impart a motion to the butterfly damper to close and reduce the area through 30 which the gases of combustion pass on the way to the chimney.

With these and other objects in view, reference is made to the accompanying sheet of drawings which illustrates preferred embodiments of this invention with the understanding that minor detail changes may be made without departing from the scope thereof.

In the drawing:

Figure 1 is a view partly in side elevation and 50 partly in vertical central section through a section of stove pipe employed as a stack leading from a furnace to the chimney and to which this invention has been applied.

Figure 2 is a view in right-hand end elevation 55 of Figure 1.

Figure 3 is a top plan view of a similar section of stove pipe to which a modified form of this invention has been applied.

Figure 4 is a view in side elevation of Figure 3. Figure 5 is a view in right-hand end elevation 5 of Figure 4.

The section of stove pipe 1, as shown in Figures 1 and 2, is provided with a butterfly damper 2 of circular form mounted upon a rod 3 passing through a diameter of the pipe 1 which is provided with a right angular exterior portion 4 extending at right angles to the surface of the damper 2 which acts not only as a counter-weight but also as an indicator as to the position of the damper. It is preferable to mount the damper 2 concentrically within the pipe 1 and form it of such a diameter that when in the closed position or in a position in which the indicator 4 is parallel to the axis of the pipe 1, approximately eighty percent of the area through which the gases of combustion pass is obstructed or cut off by the closed damper 2.

The pipe 1 is provided with a rectangular opening 5 in the bottom extending upwardly upon each side to a plane parallel to and slightly below the axis of the pipe 1 and with one vertical edge adjacent the rod 3 of the damper 2. The opening is provided with a depending rectangular housing 6 extending below the bottom of the pipe 1. The bottom opening 7 of the housing is closed by a rectangular plate or damper 8 pivotally mounted at the end adjacent the damper 2 upon a rod 9 passing through the opposite walls of the housing 6, with the free end of the plate 8 resting upon a flange 10 of an arcuate plate 11 formed concentrically with the rod 9 and extending upwardly and inwardly between the side walls of the housing and terminated at the upper extremity with a flange 12 extending radially therefrom in the direction of the rod 9 whereby the opening 7 is substantially closed by the plate 8 if it is caused to rotate about the rod 9 between the flanges 10 and 12. The under side of the plate 8 mounts a support 13 extending beyond and to the right of the rod 9 for supporting a counter-weight 14 whereby by proper adjustment of the counter-weight 14 the plate 8 would act as a valve. In the event that the pull or vacuum through the open or unobstructed pipe 1 to the chimney becomes greater than desired, then the external pressure rotates the plate 8 about its pivot 9.

To actuate the damper 2 upon the operation of the valve or plate 8, an operating rod 15 is connected to the plate 8 and to the butterfly damper 55

2 in such a relation that when the plate 8 is in the closed position parallel to the axis of the pipe 1, the damper 2 is in its open position in a plane coincident with the axis of the pipe 1. When, on account of atmospheric changes, the pull or vacuum caused by the up-draft of the chimney increases beyond that most desirable for proper combustion within the furnace, the outside atmospheric pressure upon the lower or exterior side of the plate 8 imparts a rotation to the plate about its pivot 9 which is transmitted to the damper 2 causing the damper 2 to rotate about its pivot 3 to obstruct the passage of the gases of combustion through the pipe 1 in accordance with the excess of the pull or vacuum. The arcuate plate 11 acts as a closure for the housing 6 so that as the valve 8 is rotated, substantially no atmospheric air is drawn into the pipe 1. The flange 12 is formed in such a relation that when the plate 8 engages the flange 12, the damper 2 will have completed its closing or obstructing motion and will be perpendicular to the lower side of the pipe 1. As the atmospheric conditions vary, causing a variation in the pull of the up-draft of the chimney, the action of the valve 8 upon the damper 2 compensates for these variations so that a substantially constant draft will be created for the proper combustion of the fuel within the furnace.

30 In the form illustrated in Figures 3, 4, and 5, a rectangular opening 16 is formed preferably upon the upper side of the pipe section 1. The opening 16 is provided with a closure 17 preferably curved in conformity with the curvature 35 of the pipe 1, pivoted at one end upon a rod 18 mounted in brackets 19 secured upon the exterior of the pipe 1 adjacent the furnace end of the opening 16. An arm 20 is secured centrally of the closure 17 adjacent the pivot 18, between the pivot and the free end of the closure, extending at right angles to the longitudinal center line of the closure and then bent to extend parallel thereto, clearing the side of the pipe 1. The extension is in the direction of the pivoted end 40 and extends therebeyond to mount a counter-weight 21 which is so adjusted as to normally maintain the closure in open position, as shown in Figure 4.

50 The free end of the closure 17 is provided with 55 depending and end side portions 22 and 23, respectively. The end 22 is formed on the arc of a circle concentric with the axis of the pivot rod 18 and is provided with an outstanding stop 24 adjacent the lower end thereof adapted to engage the inner side of the pipe 1 to limit the outward movement thereof, in which position it will normally be held by the counter-weight 21. The lower portion of the end 22 is preferably cut

away on the arc of a circle, as shown in Figure 5. The sides 23 depend in parallel relation from the longitudinal edges of the closure 17 and are joined to the end 22.

5 When the vacuum or pull caused by the up-draft of the chimney becomes greater than desired for proper combustion, the external atmospheric pressure will cause the closure 17 to rotate about its pivot 18 so that the curved end 22 will obstruct the passage of the gases of combustion through the pipe 1. The proportions of the dimensions of the opening 16 and arcuate end 22 are such that when the external pressure has rotated the closure 17 to cause the lower portions of the end 22 to engage the interior of the pipe 1, the said end 22 will obstruct approximately 80% of the passage through the pipe 1.

10 It is seen that by this construction the closure 17 with the end 22 forms an automatic draft regulator in which the end 22 corresponds to the 15 damper 2 and the closure 17 corresponds to the damper 8, shown in Figure 1 of the drawing.

15 A device constructed in accordance with this invention provides an automatic draft regulator which automatically obstructs or frees the passage of gas through the pipe 1 in accordance with the variable changes in atmospheric conditions 20 without admitting air at a lower temperature than the gases of combustion to enter the stack or pipe joining the furnace to the chimney, and, 25 furthermore, does not draw warm air from the furnace room into the chimney.

30 What I claim is:

An automatic draft regulator for furnaces including a cylindrical casing forming a portion of 35 and of the same diameter as the stack leading the products of combustion from the furnace to the chimney, a rectangular section cut longitudinally from said casing and pivotally mounted thereupon at the end adjacent the furnace, the 40 free end of said section provided with a curved depending portion adapted to enter and engage the side of the casing opposite said cut out section when the pivoted section lies in the normal plane of the stack, a stop on the bottom of said 45 curved portion to engage the under side of the casing to limit the outward rotation of the pivoted section, said section provided with oppositely disposed depending longitudinal sides joined to said end portion to close the opening in the casing when the said stop is engaged therewith, and a counterweight mounted upon the pivoted section to normally rotate the section to engage said stop with the casing and allow opposite rotation in proportion to chimney suction to cause the 50 curved end portion to act as a damper to restrict the gas travel through the stack.
